UNITED STATES PATENT OFFICE.

CARL J. ULMANN, OF NEW YORK, N. Y.

DESIGN FOR ORNAMENTAL TRIMMING-CORD.

SPECIFICATION forming part of Design No. 31,614, dated October 3, 1899.

Application filed September 8, 1899. Serial No. 729,881. Term of patent 7 years.

To all whom it may concern:

Be it known that I, CARL J. ULMANN, a citizen of the United States, residing in the borough of Manhattan, city, county, and State of New York, have invented and produced a new and original Design for Ornamental Trimming-Cord, of which the following is a full, clear, and exact description, reference being had to the accompanying drawings, forming part hereof, in which—

Figure 1 illustrates a side view of a section of an ornamental cord embodying my design. Fig. 2 is a transverse sectional view of the same on the line 2 2 of Fig. 1.

The leading feature of my design is an ornamental trimming-cord presenting the variegated effect of adjacent polygons of braided strands of various colors or shades, and each

of which polygons is made up of a plurality of parallel strands.

In the drawings, *a* indicates a core having on its surface a tubular covering comprising polygons *b* of various shades, and each of which polygons is formed of a series of parallel strands *c*, the whole presenting the effect of a cylindrical braid variegated upon its surface.

What I claim is—

The design for an ornamental trimming-cord, substantially as herein shown and described.

CARL J. ULMANN.
